UNITED STATES PATENT OFFICE.

BENJAMIN S. BOWERS, OF LAPRAIRIE, MINNESOTA.

ELECTRIC SWITCH.

1,211,281.

Specification of Letters Patent.

Patented Jan. 2, 1917.

Application filed September 19, 1914. Serial No. 862,553.

To all whom it may concern:

Be it known that I, BENJAMIN S. BOWERS, a citizen of the United States, residing at Lapprairie, in the county of Itasca and State 5 of Minnesota, have invented new and useful Improvements in Electric Switches, of which the following is a specification.

This invention relates to improvements in electric switches and has particular application to a switch for use in train despatchers' 10 telephone and telegraph systems.

In carrying out the present invention, it is my purpose to provide a switch of the class described whereby the telephone operator in the despatcher's office may make all 15 necessary "patches", that is, changing of wires, that an experienced telegraph or telephone engineer could make.

It is also my purpose to provide a switch 20 of the type set forth which will embrace the desired features of simplicity, efficiency and durability, which may be installed and maintained at a minimum expense and which will operate effectively under all conditions.

With the above and other objects in view, the invention consists in the construction, combination and arrangement of parts hereinafter set forth in and falling within the 25 scope of the claims.

In the accompanying drawings; Figure 1 is a view in front elevation of a switch constructed in accordance with the present invention. Fig. 2 is a view in side elevation thereof. Fig. 3 is a vertical sectional view 30 on the line 3—3 of Fig. 2. Fig. 4 is a horizontal sectional view on the line 4—4 of Fig. 2. Fig. 5 is an enlarged fragmentary sectional view through the base of the switch showing the contact fingers in edge elevation. Fig. 6 is a top plan view of the fingers. Fig. 7 is a diagrammatic view showing the 35 periphery of the drum flattened out. Fig. 8 is a fragmentary sectional view through the switch, showing one of the lightning 40 arresters for protecting the telephone and telegraph instruments.

Referring now to the drawings, 1 designates a base composed of suitable insulating material and provided at one end edge 50 with an upwardly projecting slab 2. Formed in the upper surface of the base 1 approximately centrally thereof and extending across the same transversely thereof is a concaved depression 3. Suitably secured to 55 the upper face of the base are sets of contact fingers 4, 5, 6, 7, 8, 9 and 10 and cer-

tain of the sets of fingers are connected in series in telegraph and telephone lines, while the remaining sets are connected in circuit with telegraph and telephone instruments. 60 The fingers of each set are disposed at opposite sides of the depression 3 and parallel with the fingers of the remaining sets, while the inner ends of the fingers of the respective sets are disposed adjacent to each other 65 and approximately centrally of the depression. Seated upon the upper face of the base and inclosing the fingers thereon is a semicircular housing 11 provided with segmental front and rear walls 12 and journaled in the front and rear walls of the casting centrally thereof and projecting across the same is a shaft 13, while surrounding the shaft concentrically thereof and fixed thereto is a drum 14 capable of rotation. In 70 order to rotate the drum a vertical handle 15 is mounted upon the forward extremity of the shaft 13 and preferably detachably connected thereto so that such handle may be removed from the shaft when desired. 75

Embedded in the periphery of the drum 14 are sets of contact strips 16 to 29 inclusive, each set embodying a plurality of contact strips arranged differently from those of the remaining sets and adapted to interchangeably bridge the fingers at the confronting ends thereof so that the telephone and telegraph lines may be "cross patched" or connected with one another, and connected 85 with the various sets of instruments independently of one another. Thus, one side of the telegraph line may be disconnected from the other side and connected with one side of a telephone line and vice versa, and one side of a telegraph line connected with 90 a set of telephone instruments, or a set of instruments may be cut in on a telegraph line or telephone line. In the present instance, the set of contact fingers 4 are connected 95 in series with a set of telegraph instruments, the sets 5 and 6 connected in series in telegraph lines, the set 7 connected in circuit with telegraph instruments, the sets 8 and 10 connected in series with telephone lines and the set 9 connected in circuit with telephone instruments. Thus, it will be seen that should 100 the contact fingers be bridged by the set 23 of the contact strips, for instance, the telegraph instruments connected with the sets of fingers 4 and 7 and the telephone instruments connected with the fingers 9 will be cut out of 105 service and the contact fingers 5 and 6 and 110

8 and 10 bridged whereby the telegraph and telephone lines will extend through the station, in which the switch is installed, uninterrupted. On the other hand, should the 5 set of contact strips 19 bridge the fingers a "cross patch" will be established whereby one of the fingers of the set 5 will be connected with the opposite finger of the set 8 and the remaining finger of the set 5 connected 10 with the opposite finger of the set 10. Thus, one side of the telegraph line connected with the set of contact fingers 5 will be connected with the opposite side of the telephone line connected with the set of fingers 15 8 with the set of telephone instruments connected to one of the contact fingers of the set 9 cut in, while the remaining side of the telegraph line connected with the contact fingers 5 will be connected with one side of 20 the telephone line connected with the contact fingers 10. Similarly, one side of the telegraph line connected with the contact fingers 6 will be connected with the remaining side of the telephone line connected with 25 the set of contact fingers 10 with the set of telephone instruments connected with the remaining contact fingers of the set 9 cut in, while the remaining side of the telegraph line connected with the contact fingers 6 30 will be connected with the other side of the telephone line connected with the contact fingers 8. In this condition of the switch, the fingers of the sets 4 and 7 are disconnected so that the telegraph instruments connected 35 with such fingers are cut out of service.

Normally, the contact fingers 4 and 5 are bridged by the contact strips of the set 22 whereby the two sets of telegraph instruments in the despatcher's office connected 40 with the contact fingers of the set 4 are connected, respectively, with the respective sides of the telegraph lines connected with the contact fingers 5, while the two sets of 45 telegraph instruments connected with the fingers 7 are connected respectively with the sides of the telegraph line connected with the contact fingers of the set 6. In this condition of the switch the telephone 50 line connected with the contact fingers 8 extends through the despatcher's office with one set of telephone instruments connected with the contact fingers 9 cut in, while the telephone line connected with the contact 55 fingers of the set 10 also extends through the despatcher's office with the remaining set of the telephone instruments connected with the contact fingers 9 cut in.

Suitable fuses, lightning arresters and 60 other necessary protecting devices are connected in circuit with the telegraph and telephone instruments, as usual.

From the foregoing description taken in 65 connection with the accompanying drawings, the construction, mode of operation

and manner of employing my invention will be readily apparent. It will be seen that I have provided a switch which will be found especially useful in train despatchers' offices and other offices equipped with telephone 70 and telegraph instruments and through which telegraph and telephone lines extend and whereby any set of instruments in the office may be connected in any transmission line or with one side of such line and 75 whereby one side or any or all telegraph lines may be connected with one side of any or all telephone lines and vice versa.

While I have herein shown and described one preferred form of my invention by way 80 of illustration, I wish it to be understood that I do not limit or confine myself to the precise details of construction herein described and delineated, as modification and variation may be made within the scope of 85 the claims without departing from the spirit of the invention.

Each instrument or set of instruments is protected against burning out by a lightning discharge, and in the present instance each 90 lightning arrester comprises a metal strip *a* having the lower ends bent at right angles to itself as at *b* and disposed upon and in face to face contact with the particular contact finger, the binding post carried by such 95 finger acting as a mechanical connection between the metal strip and the contact finger. The vertical portion of the finger lies parallel with the adjacent portion of the casing or housing 11 and interposed between the 100 confronting faces of the strip *a* and the housing is a mica disk *d* and disposed in face to face contact with the mica disk *d* is a metallic disk *e*. These various disks and the adjacent portion of the casing are 105 formed centrally with alining openings, and through these openings is passed a securing stud *f* having the inner end headed and the outer end screw threaded to receive a binding nut *g*, the stud *f* being insulated from the strip *a*, the disk *e* and the housing. The housing of the switch is grounded, as illustrated in Fig. 8, and as the strips *a* of the 110 respective lightning arresters are connected with the particular contact fingers of the switch connected with the telephone and 115 telegraph instruments, it will be seen that the lightning arresters are connected in shunt with the instruments. In the event of a charge of lightning traversing the conductors or wires leading to the instruments such charge will be grounded incident to the same jumping across the gap between the strips and the casing. In order to facilitate this jumping of the discharge the mica 120 strips are perforated, as clearly illustrated in Fig. 8.

The rotatable drum 14 of the switch is preferably held in the desired actuated position, and in order to so hold the drum any 125

appropriate form of lock device may be employed. In the present instance such device is carried by the front wall of the casing or housing of the switch and comprises a 5 spring pressed pin 31 slidably disposed within a tube 31' and having the outer end thereof equipped with a manipulating head 31^a and the inner end adapted to changeably enter recesses 30 formed in the front end of 10 the drum 14 concentrically thereof and corresponding to the segments on the drum.

I claim:

1. A switching system for train despatchers' offices and the like, comprising a number 15 of telegraph and telephone lines and instruments therefor, terminal connections for each line and instrument, switch contacts connected to each terminal and arranged in pairs, a movable support of insulating material having on its surface sets of electrical control devices, consisting of contact plates or insulating spaces, longitudinally arranged in sets and so disposed that the pairs 20 of switch-contacts may engage any set of 25 said electrical control devices, some of said contact plates being electrically inter-connected, and indicating means, whereby any of the various connections desired may be made by moving the support to bring the 30 corresponding set of electrical control devices and pairs of contacts into engagement.

2. A switching system for train despatchers' offices and the like, comprising a number of telegraph and telephone lines and instruments therefor in combination with a switch 35 having at each side thereof terminal connections for the telephone and telegraph lines and the instruments therefor, switch contacts connected to each terminal and arranged in pairs, and a movable support of 40 insulating material having on its surface sets of electrical control devices, each set consisting of two rows of separate contact plates or insulating spaces, and so disposed that the pairs of switch contacts engage any 45 set of said electrical control devices, some of said contact plates being electrically connected from one row to the other and other contact plates connected in the same row, and indicating means, whereby any of the 50 various connections desired can be made by moving the support to bring the corresponding set of electrical contact devices and spring fingers into engagement.

In testimony whereof I affix my signature 55 in presence of two witnesses.

BENJAMIN S. BOWERS.
